United States Patent Office.

EDWARD T. JENKINS, OF RAVENSWOOD, NEW YORK.

Letters Patent No. 86,076, dated January 19, 1869.

IMPROVEMENT IN HYDRANTS

The Schedule referred to in these Letters Patent and making part of the same.

To all whom it may concern:

Be it known that I, EDWARD T. JENKINS, of Ravenswood, Queens county, New York, have invented, made, and applied to use certain new and useful Improvements in the Construction and Operation of Hydrants; and I do declare the following to be a full, clear, and correct description of the same, reference being had to the accompanying drawings, making a part of this specification, and to the letters of reference marked thereon, in which—

Figure 1 is a top view of the wheel H.

Figure 2 is a top view of the sliding bar N.

Figure 3 is a vertical sectional view of my improved hydrant.

Figure 4 is a side elevation of the same.

In the drawings, like parts of the invention are pointed out by the same letters of reference.

The nature of my invention consists in certain improvements, as more fully hereinafter set forth, in the construction and operation of hydrants, so that freezing or wastage of water is prevented; and these improvements will be found particularly applicable to hydrants used in large cities for the extinguishment of fires.

To enable those skilled in the arts to make and use my invention, I will describe the same.

A shows an upright tube of equal calibre, and made sufficiently long to allow the plunger or piston B to rise above the discharge-opening C, upon the side of the tube A.

Upon the top and bottom of this tube A are secured the flanges A² A³.

This tube is also provided, at its lower end, with an inlet, D, for the entrance of the water from the supply pipe, with which the hydrant is to be connected in the usual manner.

E is a threaded rod inserted within the interior of the tube A, and having upon one end the wheel H, by which it is to be manipulated, and upon its opposite end, the valve I, for closing the opening D.

This rod has upon it the collars F and G, and passes through the threaded plunger or piston B.

K shows the valve-seat, which valve-seat is held between the flanges.

M is a disk or cross-bar of metal, held to its place by bolts, and provided with a central opening, through which the threaded rod is passed.

The plunger or piston B is made of India rubber, gutta-percha, leather, or any suitable material, and is threaded through its centre, to receive the rod E, and has upon its upper and lower faces the metal caps b b², also threaded centrally, and secured to the plunger, by pins or screws, to prevent their turning when the rod E is revolved.

N is a slotted bar, made to embrace the rod E between the disk M and the collar F, and is slotted, to admit of its being withdrawn from or placed in position over the rod E, by its being moved backward or forward upon the bolt over which it is passed.

Such being the construction, the operation is as follows:

The hydrant is connected with the service-pipe leading from the main pipe.

The valve I being closed, and the piston B being forced down to the valve-seat, no water can enter the hydrant.

By revolving the wheel H, the rod E, attached thereto, passes through the plunger B, making a fulcrum of it, and forcing open the valve I.

The collar G now bears upon the disk M, making a fulcrum of the collar, and causing the plunger to ascend the tube A, in which operation it is materially assisted by the pressure of the water, which follows it until it passes the exit-opening C, to which the hose is attached through which the water passes for use.

If, then, it be deemed necessary to interrupt the flow of the water, by turning the wheel in the opposite direction, the plunger will remain stationary and become the fulcrum, the rod E ascending through it and closing the valve, and the flow of water ceases, and by reversing the motion of the wheel, it is let on again.

When the water is no longer needed, and it is necessary to shut off the water entirely, and, in cold weather, to insure the operation of the hydrant, the slotted bar is placed between the disk and the collar, and serves to keep the valve open, while the wheel, being revolved in the proper direction, the plunger descends, forcing the water remaining in the tube A through the opening, down into the service-pipe, when the plunger is forced down upon the valve-seat.

The slotted bar is now removed from contact with the threaded rod, and the wheel is revolved, until the valve is brought to its seat.

Thus it will be seen that the water remaining in the tube A is entirely removed therefrom before the valve is closed, thus obviating any liability of water freezing in the hydrant, which is of too common occurrence in large cities.

My hydrant will be found simple in construction, readily and easily operated, and certainly presenting the advantages just set forth.

Having thus described my invention,

What I claim as new, and desire to secure by Letters Patent, is—

1. The combination of a tube, A, having inlet and exit-openings, with a threaded rod, E, and piston or plunger B, when the same shall be constructed and operate substantially as and for the purposes described.

2. In combination with the tube A, the threaded rod E, piston or plunger B, slotted bar N, flange F, plate M, and valve I, when the same shall be arranged and operate substantially as and for the purposes set forth.

EDWARD T. JENKINS.
